ELECTRODE STRUCTURE FOR GAS
DISCHARGE DEVICESGerald G. Carne, Rockaway, N. J., assignor to
Radio Corporation of America, a corporation
of Delaware

Application February 5, 1947, Serial No. 726,608

3 Claims. (Cl. 250—27.5)

1

My invention relates to electron discharge devices of the gas type and more particularly to grid controlled gas tubes.

One form of gas tube employing a gaseous atmosphere, preferably argon or xenon, consists of a thermionic cathode, an anode and a control electrode mounted in alignment between the two. A metal shield encloses the three electrodes and has a portion forming a screen grid between the anode and control electrode. When an A. C. potential difference is imposed between the anode and cathode of the tube a discharge takes place upon the half cycle when the anode is positive. Applying a negative bias below a critical value upon the control grid will prevent the initiation of such a discharge. The control grid bias may be shifted in a positive direction above this critical voltage value by the application of a signal voltage so as to permit the tube to conduct.

In some applications of these tubes it is desirable to control a power circuit by a small input signal current. In such instances a large resistance placed in the control grid circuit will induce a sufficiently large voltage shift of the control grid to permit tube conduction. The result is a high degree of sensitivity. Such a large grid circuit resistance is also desirable to limit the ion current flow to the grid during tube discharge.

The use of a high grid resistance has presented some serious problems. When a large impedance is placed in the grid circuit any small flow of current in the circuit will cause a shift of the voltage upon the grid toward the positive by an appreciable amount. An undesired flow of current in the grid circuit may be initiated by various conditions within the tube, the effects of which are accumulative. Such an uncontrolled shift in grid voltage causes a loss of control of tube operation by permitting an unscheduled discharge of the tube. This shift of the grid voltage may in a simple case be counteracted by increasing the grid bias voltage. However, this is not always feasible. In other cases the shift is unpredictable and erratic. In such later cases it is more expedient to eliminate the causes of such a shift in the grid control characteristic.

It is therefore an object of my invention to provide a gas control tube of improved operation.

It is also an object of my invention to provide a grid controlled gas discharge tube having a constant grid voltage breakdown characteristic.

The novel features which I believe to be characteristic of my invention are set forth with particularity in the appended claims, but the invention itself will best be understood by reference

to the following description taken in connection with the accompanying drawing, in which:

Fig. 1 is a partial sectional view of a gas discharge tube according to my invention;

Fig. 2 is a cross-sectional view along the sectional line A—A of Fig. 1; and

Fig. 3 is a circuit diagram of an application utilizing the tube of Figs. 1 and 2.

The gas tube disclosed in Fig. 1 has an envelope 10 closed at the bottom by a glass stem portion, not shown. Projecting up from the stem portion is a glass press 12 upon which are mounted a plurality of electrodes. A cathode sleeve 14 supported from press 12 is thermionically heated by a filament 15. The outer surface of the cathode sleeve 14 is covered in a well-known manner with an electron emissive coating. The anode 16 is a long narrow plate mounted axially parallel to the cathode sleeve 14. Between the cathode 14 and the anode 16 is mounted a control grid 18 in the form of an elongated metal ribbon loop.

As shown in Figs. 1 and 2 the control grid 18 is formed with flat sides enclosing a long narrow aperture 17. This aperture 17 of the control grid 25 is aligned in a parallel sense with both the cathode cylinder 14 and the anode plate 16. Completely surrounding the three electrodes is a shield comprising a tubular shield portion 20 enclosing electrodes 14, 16 and 18 and shield plates 19 and 21 closing the open ends of tubular shield 20. Mica spacers 22 and 24 hold in alignment and insulated from each other the cathode cylinder 14 and the control grid 18. The space within the tubular shield 20 is divided into two portions by a partition 26 which is fixed to the shield 20 and separates the anode 16 from control grid 17 and cathode 14. An aperture 28 is provided in partition 26 in such a way that cathode 14 is shielded from all anode field effects except those lines of force passing through aperture 28. That is, the partition 26 provides an effective shield grid structure between the anode and cathode electrodes.

A difference of potential between the anode and cathode of the tube will initiate a flow of electrons from the cathode 14 to the anode 16. This electron emission ionizes the gas of the tube thereby establishing an arc discharge between the anode and cathode. The ionization path and consequently the arc discharge are confined by the metal shields 19, 20 and 21 to the space between the anode and cathode electrodes. This well-defined arc discharge also passes essentially through the control grid aperture 17. When a sufficiently negative bias is placed upon the control grid,

breakdown of the tube and ionization of the arc discharge is prevented. A sufficiently large positive voltage applied to the grid will overcome the negative control bias and permit the gas arc discharge to take place. It is characteristic of gas tubes of this type that once this arc discharge is established the grid loses control and is unable to stop the discharge. However, a negatively biased control grid will regain control of the tube when the anode voltage is removed or reversed in polarity.

Fig. 3 discloses a relay circuit in which a relay 56 is energized by an increase in light falling upon a photoelectric tube 50. In this circuit electrical energy is derived from a source of alternating current applied to circuit terminals 32. A positive voltage is supplied to the anode 16 of the gas control tube 10 during every other half cycle of line voltage when the circuit conductor 36 of the alternating current line is positive. During the half cycles when the anode 16 of control tube 10 is positive, control grid 18 receives a negative bias through the resistance 44 which is connected to the negative conductor 38 of the circuit. Contact 46 on the resistance 44 is made adjustable so as to vary the negative value of this control grid bias. Resistance 44 is part of a shunt 40 which includes a resistance 42 between the positive portion 36 and the negative portion 38 of the A. C. circuit. In this particular application, resistance 42 may be around 20,000 ohms, while resistance 44 may be around 1,000 ohms. The cathode 14 of the gas control tube 10 is connected to this shunt 40 at 43 a point between the resistance 42 and 44. With this arrangement, the IR drop across resistance 42 determines the difference in potential between the cathode 14 and the anode 16. The anode 52 of a phototube 50 is connected directly to the positive portion 36 of the A. C. circuit. A photoelectron emitting cathode 54 of the phototube 50 is connected directly to the negatively biased grid circuit 45. A large resistance 48 preferably of from one to 10 meg-ohms is inserted into the control grid circuit 45. In the plate circuit of the control tube 10, a relay 56 is connected in series and is adapted to be operated whenever there is a current flow or arc discharge between the cathode 14 and the anode 16 of tube 10. The filament 15 for heating the cathode 14 of tube 10 derives its source of energy from the secondary of a transformer 58 whose primary is connected in the alternating current circuit.

This circuit arrangement of Fig. 3 utilizes the gas tube 10 as a control for the operation of relay 56. The conduction of tube 10 and thereby the energization of relay 56 is governed by an increase of light impinging upon the photoelectron emitting cathode 54 of the phototube 50. Contact 46 of the control grid circuit 45 may be adjusted so that as long as illumination upon the cathode 54 is less than a certain value the control grid 18 will remain sufficiently negative to prevent conduction of tube 10. When the illumination rises above this predetermined value the IR drop across resistance 48 reduces the negative potential of the control grid 18 above the critical cut-off value and the tube 10 then conducts to operate relay 56.

In order to retain proper control of the gas tube 10, in such applications as shown in Fig. 3, the negative bias of the control grid 18 should remain constant. This is possible as long as the negative charge on control electrode 18 is not diminished in any undesired manner. However, the

negative value of the charge on grid 18 may be reduced by neutralization due to the flow of positive gas ions to the control electrode and due to escape or leakage of electrons from the control electrode. The presence of the high resistance 48 in the grid circuit 45 prevents the maintenance of the desired negative grid bias if the factors neutralizing the grid are sufficiently large. In this latter case there would result a shift of the grid potential toward the positive and a consequent loss of grid control. This phenomenon of grid neutralization may be produced by a plurality of factors. Some of these factors are well recognized and have been eliminated or counteracted by various ways. Ionization of the gas in control tube 10, may occur between exposed leads within the tube or due to electronic emission between grid 18 and anode 16. Electron leakage from the control grid 18 may occur because of high difference of potential between this electrode and the anode 16. Electron emission from the grid 18 may also occur from its bombardment by positive gas ions and as its temperature increases during tube operation.

The particular problem that I am concerned with, in this case, is the reduction of the positive grid shift due to the unscheduled ionization of the gas within the control tube 10. This undesired ionization is due principally to deleterious emission from various parts within the envelope. Emission from control grid 18 can be reduced by lowering the grid operating temperature or in increasing the work function of grid electrode 18. Several experiments were tried to reduce control grid emission such as gold plating the control electrode 18; using for grid 18 a magnonickel wire which has a low electron emission; and the provision of heat radiating fins upon grid 18. I found that all of these expediencies helped to reduce the value of the positive grid shift only by approximately one-third. The situation was improved but in no way solved. I felt that it was quite possible that electron emission could be taking place from the shield grid 26 or from some other portion of the shield 20. However, this was not obvious as several attempts which I made to measure a current flow to the shield failed.

In this type of gas control tube the shield grid 26 is much closer to the anode and has an unobstructed path thereto. In contrast, the control grid 18 is entirely shielded from the anode 16. I felt that with these conditions it was conceivably possible that a much less electron emission from the shield electrode 26 than that from the control grid 18 would produce sufficient gas ionization for tube breakdown. After appropriate tests I estimated that if one microampere of control grid emission was required for tube failure due to misconduct, then approximately 0.01 microampere of shield grid emission would produce a similar tube failure. Basing my work on these tests and conclusions, I have developed a shield for this tube which has reduced the grid bias shift to an amount where it is no longer a factor.

My invention is a means to reduce shift in control voltage of the control grid by reducing shield emission through lowering the temperature of the shield 20 and of the space enclosed by this shield. This means is a provision of a dull roughened surface 23 on the outside of the grid 20. This great increase in surface area due to the roughening 23 results in a large increase in heat radiation by the shield 20.

The art teaches many methods and types of

roughened electrode surfaces. Several possible procedures such as sand-blasting, acid etching and electropolishing were tried but they did not give the desired results. In some instances an insufficient improvement in grid shift was obtained while other methods proved impractical from a standpoint of tube manufacturing. The problem was further complicated by the fact that the tube with which I was working was a gas tube in which the gas pressure was critical. Thus, a method of carbonizing the shield was found to change the gas pressure within the tube due to the carbon absorbing the gas.

I discovered that the best method of reducing the shift in the grid characteristic was by spraying the shield 20 with a coating of nickel oxide which when reduced by hydrogen firing presented a dull rough nickel surface 23. The nickel oxide was mixed with a nitrocellulose binder. This coating mixture can be applied to the shield 20 by several ways such as painting, spraying, or dragging. The coated shield is air dried and then placed in a hydrogen furnace for approximately 10 minutes at 1000° C. During this hydrogen firing the nickel oxide is reduced to finely divided nickel particles. At this furnace temperature, the nitrocellulose binder is burned off and the nickel particles sintered to the surface of the metal shield 20. The time of firing and the furnace temperatures are not critical as the same reaction can take place at lower temperatures such as 700° over a longer period of time.

This method of providing a roughened nickel coating 23 to the shield electrode 20 has resulted in reducing the grid voltage shift from approximately 5 volts to less than 0.5 volt, a point where the grid shift is not a problem. There may be several explanations for this improvement of tube operation but undoubtedly the greatest contributing factor is reduction of the operating temperature within the interelectrode space enclosed by the tube shield 20. It is apparent that the increased surface of radiation of the shield, as well as its dull coloration, lowers the temperature of grid 26 and shield 20 to a point where a gas ionizing electron emission from the shield grid 26 or any part of the shield 20 to anode 16 is at a minimum.

While certain specific embodiments have been illustrated and described, it will be understood that various changes and modifications may be made therein without departing from the spirit and scope of the invention.

What I claim as new is:

1. An electron discharge device comprising a sealed envelope, a gaseous medium within said envelope, an anode electrode mounted within said envelope, an electron emitting electrode spaced within said envelope from said anode electrode, a non-emitting control electrode mounted between said anode and said electron emitting electrodes, a tubular metal shield within said envelope enclosing all of said electrodes, said shield having an apertured portion extending between said anode and said control electrode, said shield having a rough coating of nickel metal particles sintered to the outer surface thereof to minimize electron emission between any portion of said shield and said anode electrode.
2. A gaseous discharge device comprising a sealed envelope, an anode mounted within said envelope, an electron emitting cathode spaced within said envelope from said anode, a shield electrode within said envelope adapted to be negatively biased relative to said anode and having a portion extending between said anode and cathode electrodes, a rough coating of nickel metal particles sintered to a portion of the surface of said shield electrode to minimize electron emission between said shield and said anode electrode.
3. A shield assembly adapted to be disposed at a negative bias within the sealed envelope of a gaseous electron discharge device, comprising a tubular metal body portion for enclosing the electrodes of said tube and a metal plate closing each end of said tubular body to confine the gaseous discharge of the tube in the space within said tubular body portion, a rough coating of nickel metal particles sintered to the outer surface of said cylindrical body portion to minimize electron emission from said shield.
